(57) CLAIM

The ornamental design for a drum with spice dispenser, as shown.

DESCRIPTION

FIG. 1 is a side plan view of a drum with spice dispenser, showing my new design;

FIG. 2 is a top plan view thereof;

FIG. 3 is a bottom plan view thereof; and,

FIG. 4 is a side perspective view thereof.

Portions of the design shown in broken or dashed lines in the drawings are for illustrative purposes only, and forms no part of the claim design.
